(57) **CLAIM**

The ornamental design for an optical communication module, as shown and described.

DESCRIPTION

FIG. 1 is a front elevation of an optical communication module showing our new design;

FIG. 2 is a top plan view thereof;

FIG. 3 is a bottom plan view thereof;

FIG. 4 is a rear elevation thereof;

FIG. 5 is a left side elevation thereof;

FIG. 6 is a right side elevation thereof;

FIG. 7 is a perspective view thereof;

FIG. 8 is a cross-section thereof taken along line A—A in FIG. 1;

FIG. 9 is a cross-section thereof taken along line B—B in FIG. 2;

FIG. 10 is a modified embodiment of the design shown in FIGS. 1 through 9;

FIG. 11 is a top plan view thereof;

FIG. 12 is a bottom plan view thereof;

FIG. 13 is a rear elevation thereof;

FIG. 14 is a left side elevation thereof;

FIG. 15 is a right side elevation thereof;

FIG. 16 is a perspective view thereof;

FIG. 17 is a cross-section thereof taken along line C—C in FIG. 10; and,

FIG. 18 is a cross-section thereof taken along line D—D in FIG. 11.
